UNITED STATES PATENT OFFICE.

FRANK S. KING, OF NEW BEDFORD, MASSACHUSETTS.

DESIGN FOR A HOOK.

48,116.

Specification for Design.

Patented Nov. 9, 1915.

Application filed February 20, 1915. Serial No. 9,731. Term of patent 7 years.

To all whom it may concern:

Be it known that I, FRANK S. KING, a citizen of the United States, residing at New Bedford, in the county of Bristol and State of Massachusetts, have invented a new, original, and ornamental Design for Hooks, of which the following is a specification, reference being had to the accompanying drawing, forming a part thereof.

Figure 1 is a front elevation of a hook,

showing my new design; Fig. 2 is a side elevation; and Fig. 3 is a plan view.

I claim:

The ornamental design for a hook, as shown.

FRANK S. KING.
